UNITED STATES PATENT OFFICE.

FRED LOBNITZ, OF CROOKSTON, SCOTLAND.

COMBINED SUBAQUEOUS ROCK CUTTER AND DREDGE.

Application filed May 14, 1921. Serial No. 469,483.

To all whom it may concern:

Be it known that I, FRED LOBNITZ, of Ross Hall, Crookston, Renfrewshire, Scotland, a subject of the King of Great Britain, 5 have invented certain new and useful Combined Subaqueous Rock Cutters and Dredges, of which the following is a specification.

At present, in effecting sub-aqueous excavations where the bed to be operated on consists of rock, boulders, stone, hardened earth or other substance not readily removable by simple excavation or dredging, it is customary first to clear the bed of overlying 10 substance, loose boulders, or the like, or to effect such clearing as may be practicable, by dredging, then to move away the dredge and substitute therefor a barge or other buoyant structure carrying a rock cutter 15 by which the bed is broken or disintegrated and then, finally, to move away the rock cutter and reinstall the dredge by which the spoil is then removed and disposed of in suitable manner. In some cases the initial 20 clearing operation can be omitted and the breaking or disintegrating of the bed effected in the first instance but this method of excavation, with or without the initial clearing operation, is a lengthy process involving 25 the use of two separate vessels, one carrying the dredging apparatus and the other the rock cutter, and the expenditure of much time and labour in substituting one vessel for another, mooring and unmooring such 30 vessels and other work not directly productive in effecting the excavation. Further, as the average dipper or grab dredge, such as is employed for this purpose, is capable 35 of removing or excavating spoil more 40 quickly than the average rock cutter can produce it by breaking or disintegrating the bed on which it is working it is impracticable to maintain both apparatus in full work simultaneously whilst, owing to practical 45 difficulties, it has heretofore been impracticable to embody a rock cutter and a dredging dipper or grab in a single vessel.

The present invention consists in combining with a dipper dredge or with a grab 50 dredge or sub-aqueous excavator, a rock cutting apparatus, in such manner that the cutter can be operated from the usual boom or jib of the dredge alternatively with the operation of the usual dipper or grab, both 55 operations being, preferably, effected by the same winding mechanism and crew. In this

way the operation of breaking up the rocky or other bed of a river or other water way and the dredging of the spoil can be effected by the same vessel in a very cheap and effective manner. The cutter is suspended 60 over the boom or the jib of the dredge and operates within a guide freely suspended from the boom or jib. The dipper or the grab, as the case may be, is operated in the usual way. As the boom or jib of the dredging vessel can be caused to describe a series 65 of arcs, from side to side of the dredge, the breaking and dredging operations can be carried on over a large area whilst the dredge itself is gradually moved forward. 70

In one constructional form the vessel is provided with stabilizing spuds and pivotal boom, both structures well known in connection with dipper dredges, and carries a single operating winch. The dipper (or 75 grab) is mounted in connection with, or suspended from, the boom in known manner and the cutter and its guide are suspended by wire ropes mounted in sheaves at the extremity of the boom and connecting the cutter with the operating winch and the guide with an auxiliary winch suitably carried on the vessel and utilized for the purpose of raising and lowering the guide as 80 desired; or the guide may be adjusted by temporarily attaching it to the cutter. 85

In operation, say for the excavation of sub-aqueous rock by a dipper dredge, first, the dipper only is connected with the boom and operating winch and utilized, in known 90 manner, to clear the surface of the rock ready for breaking. The dipper is then unshipped on to the deck of the vessel, or on to another vessel alongside, or is left in position or is otherwise disposed of, and the guide for the rock cutter is suspended from the end of the boom and the cutter, suspended therein, is attached by its winding rope or ropes to the operating winch. 95 The vessel is then stabilized on its spuds in known manner and the rock cutter caused to operate in semicircular arcs about the pivot of the boom and, as each arc is completed, the vessel is moved forward and the operation repeated. After a sufficient area has 100 been broken the cutter and its guide are removed from the boom and the dipper brought into operative position and the vessel can then be caused to work back over the area broken up by the cutter, with the 105 dipper operating to dredge the spoil. This 110

cycle of operations, or any part thereof, can be repeated as often as necessary or convenient during the process of excavation.

The cycle of operations would be similar in the case of a combined grab dredge and rock cutter.

In order that the invention may be clearly understood and readily carried into effect or practice two sheets of drawings are hereunto appended whereon are illustrated, by way of example, a dredge of the dipper type in which the rock cutter is arranged to operate alternatively with the dredging dipper.

On the drawings, Figs. 1, 2 and 3 are side elevations, end elevation, and plan respectively, of the combined rock cutter and dipper dredge. Fig. 4 is an enlarged sectional view of the cutter and its guide whilst Fig. 5 is a cross section on the line 5-5 Fig. 4.

Referring now to the drawings, in the construction illustrated, A is the vessel, B the operating winch thereon, C the stabilizing spuds and D the boom mounted upon the pivoted table D', all of known construction and, in Figs. 1, 2 and 3, E and E' indicate the dredging dipper and the dipper arm in dotted lines. The dipper E is arranged and operated in known manner.

As shown at Figs. 1 to 3 the rock cutter 11 is suspended, by a double rope suspension 10 passing over double sheaves 7, 6 and 5 to the barrel 4 of the winding winch B. Preferably on the same pin as the sheaves 7 is a third sheave 7^a for carrying the dipper-operating rope. By operating this winch, in known manner, the cutter can be raised and then allowed to fall and strike 40 the rock, a coil clutch as referred to in my prior specification of the United States No. 874,217 dated 17th December, 1907, being arranged in connection with the winch in order to facilitate the raising and dropping 45 operation. The cutter is adapted to operate within the guide 9 which is freely suspended by means of two wire ropes or chains 12 (see Figs. 2 and 4 but not at Fig. 1 being there removed for clearness as they 50 are in the same plane as rope 10) from stoppers 13 at the end of the boom D. The guide 9 preferably consists of a long metal tube 14 which is lined with wood 15. It can be raised and lowered, as desired, by 55 merely altering the length of the suspension cable 12.

Assuming the normal or average cycle of operations has to be performed, (that is to say, the sub-aqueous bed has first to be 60 cleared, then broken or disintegrated and, finally, the spoil removed), the dredging dipper is first operatively mounted on the vessel, the rock cutter and guide being removed out of the way, and the initial dredging or clearing operation performed, in

known manner, by stabilizing the vessel on its spuds and operating the dipper in arcs about the pivot of the boom D, the vessel being moved forward as each arc is completed. The double rope 10 after being 70 detached from the cutter 11 can be readily connected to the dipper as indicated in dotted lines at 10^a. When the clearing operation has been performed over a sufficient area the dipper E is unshipped on to the 75 deck of the vessel, on to a barge alongside, or otherwise disposed of and disconnected from the operating winch B. The guide 9 and cutter 11 are then suspended from the boom D, and operatively connected with 80 the winch B, and the rock-cutting operation performed by stabilizing the vessel on its spuds and operating the cutter in arcs about the pivot of the boom D in a manner similar to that in which the initial dredging 85 operation was performed. Finally, when the cleared area has been broken, the cutter 11 and guide 9 are unshipped and the dipper re-installed when the final excavation of the spoil can be effected in a manner similar to that in which the initial clearing 90 operation was carried out.

In other forms of the invention the construction or adaptation may be such that the dredging apparatus and rock-cutting apparatus can be so arranged as to obviate the necessity for unshipping one and installing the other each time it is desired to change over from one operation to the other. In this case the central sheave 7^a shown at the end of the boom at Figs. 2 and 3 is utilized, a dipper operating rope (as at 10^a) being passed over this sheave and thence to a dipper operating drum on the winch B. With such an arrangement both apparatus may still be operated from a single operating mechanism, in which case means would be provided for making fast the apparatus for the time being not in use or separate operating mechanism may be provided for each.

Having now fully described my invention what I claim and desire to secure by Letters Patent is:—

1. In combination with a dipper dredge, a cutter, a guide within which said cutter is suspended, a boom on the dredge, flexible members by which said guide is freely suspended from said boom so as to move laterally in all directions, means carried by said dredge and upon which said boom is pivoted whereby said cutter may operate upon ground not directly underneath said dredge, mechanism for operating said cutter, duplex ropes extending from said mechanism along said boom to said cutter, three sheaves mounted at the end of said boom, the two outer sheaves for carrying said ropes, and the middle one for carrying the dipper-operating rope.

2. In combination with a dipper dredge, a cutter, a guide within which said cutter is suspended, a boom on the dredge, duplicate chains by which said guide is freely suspended from said boom so as to move laterally in all directions, a pivoted table carried by said dredge and upon which said boom is mounted whereby said cutter may operate upon ground not directly underneath said dredge, mechanism for operating said cutter, duplicate sheaves at the end of said boom, duplicate sheaves near the base of said boom and above said table, duplicate sheaves beneath said table, duplex ropes extending from said cutter-operating mechanism over all said sheaves to said cutter. 35
3. In combination with a dipper dredge, a cutter, a guide within which said cutter is suspended, a boom on the dredge, duplicate chains by which said guide is freely suspended from said boom so as to move laterally in all directions, a pivoted table carried by said dredge and upon which said boom is mounted whereby said cutter may operate upon ground not directly underneath said dredge, a winch for operating said cutter, duplex ropes extending from said winch along said boom to said cutter, a pin near the end of said boom, three sheaves upon said pin, the two outer sheaves for carrying said ropes, and the middle sheave for carrying the dipper-operating rope, duplicate sheaves near the base of said boom, and duplicate sheaves beneath the base of the boom to guide said duplex ropes from said winch up through the pivotal centre of said base to the sheaves 40 at the end of the boom. 45
- In testimony whereof I affix my signature in presence of two witnesses.
